United States Patent Office

Des. 219,410
Patented Dec. 8, 1970

219,410

AIRCRAFT

Stanley A. Hall, Sunnyvale, Calif., assignor to Lockheed
Aircraft Corporation, Burbank, Calif.

Filed Sept. 23, 1969, Ser. No. 19,262

Term of patent 14 years

Int. Cl. D12—07

U.S. Cl. D71—1

Des. 219,410

PAGE 2

FIG. 1 is a perspective view of an aircraft showing my new design,

FIG. 2 is a side elevational view thereof,

FIG. 3 is a top plan view thereof,

FIG. 4 is a front elevational view thereof, and

FIG. 5 is a bottom plan view thereof.

I claim:

The ornamental design for an aircraft, as shown.
